J. M. Albert
ATTORNEY

UNITED STATES PATENT OFFICE.

ANTON LEDERER, OF VIENNA, AUSTRIA. ASSIGNOR TO WESTINGHOUSE LAMP COMPANY, A CORPORATION OF PENNSYLVANIA.

ELECTRIC GAS LAMP.

Application filed July 18, 1914, Serial No. 851,836. Renewed May 3, 1921. Serial No. 466,401.

To all whom it may concern.

Be it known that I, ANTON LEDERER, a subject of the Emperor of Austria, and a resident of Vienna, Austria, have invented 5 certain new and useful Improvements in Electric Gas Lamps, of which the following is a specification.

This invention relates to electric gas lamps, that is to say electric lamps in which 10 a gas or mixture of gases, particularly the so called rare gases such as neon, helium, argon, krypton, etc., forms the light giving medium.

In order to reduce the amount of the potential drop required to operate electric gas lamps of this kind it has already been proposed to form the electrodes of the alkali metals or their alloys. Electrodes consisting of an alkali metal however have great 15 disadvantages chiefly arising from the fact that the alkali metals are very easily oxidized and also burn very easily, which renders it very difficult to introduce electrodes of these metals into the lamp and at the same 20 time preserve their bright surface. A further disadvantage is that the oxides of these metals attack the glass parts of the lamp. Alloys of the alkali metals, for instance certain alloys of sodium and potassium, are 25 liquid, which fact involves the disadvantage that the lamps have to be handled with the utmost care in order to retain the electrodes in the vessels destined for that purpose. Also, the solid alkali metal electrodes re- 30 quire special receptacles attached to the lighting tube and such receptacles must be provided with some kind of partition or 35 guard, such for instance as a piece of wire gauze to prevent the contents of the recep- 40 tacles from escaping therefrom. It follows that electrodes of the alkali metals or their alloys endanger the certainty of operation 45 of the lamp and also render the construction of the lamp complicated, so that the advantages which these electrodes offer are almost negatived by the disadvantages.

According to the present invention electric gas lamps may be operated with the same low potential drop as is possible by 50 the use of alkali metal electrodes, with the further advantage that the electrode material may be of any one of a large number of

suitable light or heavy metals such for instance as aluminium, magnesium, tungsten, or the like. In order to enable lamps having such electrodes to be operated with a small potential drop the lighting tubes contains small quantities of one or more of the alkali metals in a liquid or solid state, preferably in the form of a deposit. In most 55 cases mere traces of these metals or alloys are sufficient. Such lamps will operate with certainty and are extremely simple in their construction and manufacture.

The alkali metal or metals may for example be introduced in a gaseous form in the following manner: A small quantity of an alkali metal or of an alloy of such metals is placed in a small addition or pocket attached to the lighting tube of the lamp. 60 By suitable heating the metal or alloy is caused to vaporize and as soon as the vapour has entered the lighting tube so that it can deposit on the inner wall of the tube, the above mentioned addition or pocket is sealed 65 off and the lamp finished in the usual manner.

The lighting tube of the lamp as such is preferably left free of any traces of the alkali metal or metals, which latter are preferably restricted to the vicinity of the electrodes. It is even sufficient to restrict the presence of the alkali metal or metals to the region of the anode alone. In this case 70 the presence of the alkali metal or metals 75 is preferably manifested in the form of a deposit of the metal or metals on the inner wall of the lamp tube in the region of the anode. In this way that part of the lighting tube which forms the real source of 80 light may be left free of any deposit or traces of alkali metals, with the advantage 85 that the light emission of the lamp is in no way interfered with.

The constructional details of the lamp are 90 of no importance, the essential feature of the invention being the presence of small traces of one or more of the alkali metals in the interior of the lamp.

However, a better understanding of the 100 invention may be had by reference to the accompanying drawing which illustrates diagrammatically a conventional type of electric gas lamp having temporarily connect-

ed thereto a vessel from which the alkali metal or metals may be vaporized to form a deposit within the lamp.

More particularly, the drawing illustrates 5 a glass envelope 4 of a shape having enlarged cylindrical end portions 5 and 6 connected by a light-giving tube portion 7, the tube being filled with a rare gas or a mixture of rare gases. The electrodes 9 and 10 10 may be sealed into the cylindrical portions 5 and 6 by means of leading-in conductors 12 and 13 respectively.

To the lower end of the tube 5 a receptacle 15 is sealed and opens thereinto and 15 contains a quantity of an alkali metal, such, for example, as sodium. At the upper end of the cylindrical portion 6 is an exhaust tube 16 shown as sealed, which operation is performed after the tube has been exhausted in any approved manner.

After the exhaustion of the envelope 4 and either before or after the introduction of the gaseous atmosphere, the alkali metal contained in the receptacle 15 may be vaporized by heating the latter, as with a Bunsen flame. The metal vapor thus enters the envelope of the lamp and is deposited within the same, particularly in the vicinity of the electrodes 9 and 10 and obviously on the 25 electrodes themselves, as well as on the inner wall of the glass envelope. The amount of metal vaporized need be very small, and preferably is restricted to a thin metallic deposit which will only very slightly impair 30 the radiation of light emitted from the light-giving portion 7 of the envelope 4. After the introduction of the alkali metal within the lamp the pocket 15 may be sealed off as at 17.

40 While I do not desire to be restricted to any theory of operation of a lamp made according to my invention it appears that the presence of a slight amount of alkali metal on the electrodes diminishes the starting voltage of the lamp and this deposit is especially valuable when the lamp is filled 45 with a rare gas, particularly neon, as by employing these features and having proper regard for constructional details a lamp may 50 be produced which will start on 110 volts, A. C. or D. C.

The true function of the alkali metal, however, may be other than that mentioned but it is to be understood that the essential 55 feature of the invention is the presence of a relatively small quantity of one or more of the alkali metals deposited within the lamp. It should also be understood that a method has been provided whereby one of these 60 metals may be introduced into a lamp so that a beneficial action is exerted thereon, particularly with respect to lowering its starting voltage.

In the appended claims the term "alkali 65 metals" is employed in specifying the for-

mation of a thin deposit within the lamp, but I wish it to be understood that in using this term I contemplate the alloys of such metals.

I claim as my invention:

1. An electric gas lamp comprising an envelope enclosing a gaseous atmosphere, non-alkali metal electrodes and a relatively small quantity of an alkali metal in the form of a deposit. 70

2. An electric gas lamp comprising an envelope enclosing neon, non-alkali metal electrodes and a relatively small quantity of an alkali metal in the form of a deposit. 75

3. An electric gas lamp comprising an envelope enclosing a rare gas, non-alkali metal electrodes and a relatively small quantity of an alkali metal in the form of a deposit. 80

4. An electric gas lamp comprising an envelope enclosing a gas, non-alkali metal electrodes and a relatively small quantity of an alkali metal affixed to at least one of said electrodes. 85

5. An electric gas lamp comprising an envelope enclosing a mixture of gases, non-alkali metal electrodes and a relatively small quantity of an alkali metal on at least one of said electrodes. 90

6. An electric gas lamp comprising an envelope enclosing a mixture of rare gases, non-alkali metal electrodes and a relatively small quantity of an alkali metal on at least one of said electrodes. 95

7. An electric gas lamp comprising an envelope enclosing neon, non-alkali metal electrodes and a relatively small quantity of an alkali metal on at least one of said electrodes. 100

8. An electric gas lamp comprising an envelope enclosing neon, aluminum electrodes and a thin layer of an alkali metal deposited on said electrodes. 105

9. An electric gas lamp comprising an envelope enclosing neon, non-alkali metal electrodes having deposited as a coating thereon a relatively small quantity of an alkali metal. 110

10. An electric gas lamp comprising an envelope enclosing neon, non-alkali metal electrodes having a relatively thin coating thereon consisting of a small quantity of an alkali metal. 115

11. An electric gas lamp comprising an envelope enclosing a gas, non-alkali metal electrodes and a relatively small quantity of an alkali metal combined with at least one of said electrodes. 120

12. An electric gas lamp comprising an envelope enclosing neon and electrodes within said envelope, at least one of said electrodes comprising a non-alkali metal and a small quantity of an alkali metal. 125

13. An electric gas lamp comprising an envelope enclosing a rare gas, non-alkali metal electrodes and a relatively small quan- 130

5
tity of an alkali metal within said envelope.

14. In an electric discharge device, an electrode comprising a non-alkali metal having combined therewith a small quantity of an alkali metal.

15. In an electric discharge device, an electrode comprising a non-alkali metal having a coating of an alkali metal formed thereon.

10
16. The method of lowering the potential drop in an electric gas lamp provided with non-alkali metal electrodes which comprises depositing a relatively small quantity of an

15
alkali metal on at least one of said electrodes.

17. The method of lowering the potential drop in an electric gas lamp having non-alkali metal electrodes, which comprises depositing a relatively small quantity of an 20 alkali metal in the interior of the lamp.

In testimony whereof I have hereunto subscribed my name this 9th day of July, 1914.

ANTON LEDERER.
